UNITED STATES PATENT OFFICE

2,255,511

PREFABRICATED BUILDING CONSTRUCTION

John Muller, Brooklyn, N. Y.

Application September 23, 1936, Serial No. 102,138

13 Claims. (Cl. 72—1)

My invention relates to new and improved structural units and methods of constructing a building of more than one story in height in which all of the structure is of pre-fabricated sections, although the separate portions thereof are useable in other locations.

The present invention is designed to produce cheaply, structural units that will have insulating qualities as to sound and temperature, be moisture-proof, light in weight yet of the desired rigidity, capable of mass production, easy to handle, and simple to erect.

It is an object of my invention to mold light weight structural units complete in themselves and such that when assembled each unit will interlock with another to form the walls and partitions of a building of more than one story in height and of the required strength and rigidity.

It is another object of my invention to produce a molded post or building strut unit complete in itself comprising a central core or magnesium or magnesium alloy metal embedded in a magnesia cement mortar of desired thickness, and which may have its exposed surfaces finished in accordance with any desired specifications.

Another object of my invention is to produce a molded floor unit complete in itself, and of desired thickness, length and width which can be locked in place to the aforementioned post units.

Another object of my invention is to provide a molded partition unit for forming the walls of rooms in which the units can be readily dismounted, moved and re-erected to suit individual desires, and in which the position of one or more of the units may be changed to suit requirements without disturbing the other units, and then re-locking the units in place.

A further object of my invention is to provide a molded unit in which two or more plastic substances of different textures and strengths may be used to give additional strength to the units at desired points.

A still further object of my invention is to provide a molded hanging ceiling having desired acoustical properties and which can be readily attached and detached as required.

Other and additional objects and advantages will appear as the following description proceeds in conjunction with the accompanying drawings, illustrating one form of the novel features of construction and combination of parts of my invention, in which—

5 Figure 1 is a perspective view of a physical embodiment of my invention showing the first floor of a building with the end, side and center walls, flooring and room partitioning in place, and ready to receive a second and additional floors of similar construction.

10 Fig. 2 is a vertical section taken through post units of the building from the foundation to the roof showing the various floor, ceiling and roof units assembled to it, parts being broken away.

Fig. 2A illustrated an assembly at the peak of the roof of the house indicated in Fig. 2.

15 Fig. 3 is a horizontal cross section looking down upon a post and adjoining wall units showing a means for locking the same in place.

Fig. 4 is a similar view as in Fig. 3 but illustrating one of the corner post units.

20 Fig. 5 is a horizontal cross section looking down upon so much of a wall unit to show a door jamb mounted in place.

Fig. 6 is a partial vertical section through one portion of a building showing post units, both outside walls, and a center wall, and the mounting of floor units to said post units, parts being broken away.

25 Fig. 7 is a fragmentary vertical section showing in detail the post unit and supporting means for the floor units when the junction thereof occurs between posts.

30 Fig. 8 is an elevational view of a wall section showing post and wall units parts being shown in section to illustrate fastening means between the walls sections and the posts.

35 Fig. 9 is a horizontal cross section of a portion of a wall showing the mounting of a window frame, parts being broken away.

Fig. 10 is an enlarged longitudinal cross section through the floor or wall units showing means for fastening the units to each other.

40 Fig. 11 is a front elevation of the demountable partitions, with parts broken away for clarity, showing the locking and lock receiving means for each unit.

Fig. 12 is an end elevation of one of the demountable partitions shown in Fig. 11.

Fig. 13 is a horizontal cross section of the demountable partitions shown in Figs. 11 and 12.

45 Figs. 14 and 15 are respectively enlarged cross sectional and plan views showing the demountable base board with means for quickly attaching and detaching the same in place.

Fig. 16 is an enlarged sectional detail showing demountable base boards mounted in place.

50 Figs. 17 and 18 are cross sectional views, parts being broken away, showing means for mounting

and suspending hanging ceilings, the figures showing different exterior finishes respectively.

Fig. 19 is a vertical section on the line 19-19 of Fig. 21 between adjoining ends of two center ceiling units.

Fig. 20 is a vertical section between adjoining ends of two side ceiling units.

Fig. 21 is an enlarged plan view of the clip portion of Fig. 19.

Fig. 22 is an enlarged detail of a modified securing means for clamping adjacent wall sections together and locking them in place.

Fig. 23 is a plan view of a floor unit, which is also typical of a wall unit except for the inclusion of materials of two different textures.

Referring to the drawings, Fig. 1 represents the first floor of a building assembled with my structural units and consists of front wall 10, rear wall 18, side walls 20, 22, center wall 24, partitioning 26 and flooring 28. The walls are 20 formed of a plurality of molded wall sections 12 and upright posts or studs 17. These are shown in alternate relation, but it will be apparent from the following description that two or more wall sections may be mounted between each pair of posts. By way of example, a door 14 and a window 16 are shown mounted in the front wall.

As shown in Fig. 2 the floor units 28 of the ground floor are supported on the foundation 30. The floor unit 28 is provided with a surrounding 30 metal frame 32 which may be of magnesium alloy metals, and is channeled on all sides as indicated at 34 for the reception of tongues 33 to support the same, as will be more fully described.

The frame 32 is of the desired depth for flooring purposes and is filled with an insulating material 36 which imbeds the channel 34 except those end portions 38 which support and locate the posts or studs 17 of the building. The end portions 38 are filled with a finer textured insulating material 39 which also embeds and surrounds the channels 34.

The insulating material 36 may be made according to any desired formula. One material I have found satisfactory is a composition insulation which consists in mixing excelsior or similar shavings or chips with a cement-like mortar composed of eighty parts of magnesium oxide, eighty parts of magnesium chloride, and an equal quantity of water, to which approximately thirty parts of powdered asbestos is added. Likewise the insulating material 39 may be made according to any desired formula. One material I have found satisfactory is made substituting sawdust for the excelsior in the above composition. Because of its finer ingredients a more dense mass is formed.

While wet both these mixtures are poured into the frame and spread out so as to fill the frame but not extend beyond the edges thereof. The mixtures are then allowed to dry or set, in which condition each becomes a hard and solid mass with innumerable pores and air spaces, and the two are homogeneously united.

As shown in Fig. 23, there is also embedded in the insulation 36 a plurality of tubes 41 for receiving locking bolts 43. As shown in Fig. 10, each bolt screws into a nut 45 which may be welded in channel 34 and together with nut 47, applied to the opposite end of the bolt, secures 70 and locks in place the adjacent floor unit.

The floor sections or units may be completed by surfacing one side with suitable material 42 for the ceiling, and the other side with suitable material 44 for the floor, these surface materials 75

covering the frames and the insulating material to within the distance required for the setting of the posts 17. The floor surface 44 may have imbedded therein a wire mesh 46 to increase the resistance of the composition to shocks, etc. For covering the exposed surface of the ceiling I may use a mortar or plaster or cement, as it may be termed, similar to the mixture used with the excelsior except that in some instances additional powdered asbestos is used. The floor surface 44 will be of desired thickness and strength and may be a composition of magnesium oxychloride cement, wood flour, asbestos powder and color. The surface coverings 42-44 will overlay the edges of the respective frames 32 so that when the floor units are assembled together a continuous surface is provided as indicated in Fig. 1. Of course, the floor surfaces 44 with the wire mesh 46 may be applied after the floor sections 28 have been locked in place.

The various posts 17, of required height, are placed for support of the wall units and floor sections as shown in detail in Figs. 2, 3, 4 and 5. Each post consists of a channeled magnesium-alloy metal column 50 of H construction, except for legs 52 and 54 extending from the top and bottom of the column 50 respectively. As indicated at 55, the column 50 is embedded in a cement, which may be composed of 15 parts of magnesium oxide, 15 parts of chloride, 85 parts of pumice stone and a quantity of water sufficient to bring the mix to 20° Baumé, and a wire mesh 64 may be imbedded in the composition. The cement 55 may be molded to whatever shape is desired for the post unit 17, i. e., a corner post as shown in Fig. 4 or a side wall post as shown in Fig. 3. The post may be completed by surfacing the outside and the inside thereof as indicated at 66 and 68 and for this purpose I may use on 40 the outside surface a cement of a mixture composed of 15 parts of magnesium oxide, 15 parts of magnesium chloride and 85 parts of coral sand, pulverized quartz, or finely ground marble, or marble with color, and an equal quantity of water, and for the inside surface a cement-like mixture composed of eighty parts of magnesium oxide, eighty parts of magnesium chloride, and an equal quantity of water, to which approximately thirty parts of powdered asbestos is added.

Plates 56 and 58 (Fig. 2) extend respectively across the top and bottom of post 17, including column 50, and inwardly from the legs 52 and 54. The plates may be welded to the exposed parts of the post before the plastic material is applied. Tongues 60 and 62 are attached to the respective plates by screws or the like, the tongues fitting into channels 40 molded in the portion 38 of the floor units 28. The tongues 60 and 62 act as cross supports tying the post units 17 and the floor units 28 together.

The assembly of the outer walls and several floor sections may be accomplished as follows: The lower floor sections 28 are rested or secured in place upon the foundation 30, a post 17 is mounted in place with its leg 54 secured to the frame 32 of the floor unit and the tongue 60 in the groove 40 of the floor unit, while the plate 58 rests upon the frame 32; after the wall of the first floor of the house is assembled as hereinafter described, each floor unit 28 for the second floor of the house is set in place and the upper leg of each post 17 is secured to the frame 32 of the newly laid floor unit 28 with the tongue 62 engaging the lower groove 40 in that floor unit 28

and the frame 32 resting upon the plate 58; after the second floor is laid, each post 17 of the wall for the second floor of the house is put in place with the lower leg 54 thereof secured to the exposed frame 32 and the tongue 60 of its lower plate engaging the upper groove 40 in the second floor unit 28; after this wall for the second floor of the house is completed, additional floors may be built up as described, and finally the ceiling of the upper floor and the roof are assembled in place as will be more fully described.

A method of assembling wall units 12 in position is illustrated in Figs. 3, 4, 5 and 8. Fig. 3 shows a portion of the method of locking the wall sections to a post unit 17. Vertical grooves 51 are molded on each side of the posts 17, in which grooves are received tongues 53 that also fit in the side channels 34 of the surrounding frames 32 of the side wall units. The tongues 53 and all the other positioning tongues hereinafter referred to wherever possible extend the full length, width or height of the building or so as to engage as many contiguous sections as possible.

Fig. 8 shows an additional method of securing the wall units to the post 17. As explained above, the wall units 12 have transverse tubes 41 extending thereacross, through which pass bolts 43, the screw-threaded end of which is received in an appropriate screw threaded hole in the column 50. The head 75 of each of these bolts 43 fits within and contacts the bottom of the channel 34 of the frame 32 of the wall unit. Embedded in the cement of the post are aligned transverse tubes 71. Bolt 72 passes through tubes 70 and a registering hole in the H column 50 and screws into a nut 78 which is located in the channel 34 and welded thereto the frame 32 of the adjoining wall unit 12, the head 79 of the bolt 72 abutting the exposed edge of a tube 70.

In cases where a number of wall units 12 are assembled together between posts 17, the arrangement of Fig. 10, which relates specifically to floors, may be used. There the tubes 41 of each adjacent wall unit are offset or staggered with respect to those of the next adjacent wall unit. A nut 45 is welded to the base of the channel portion 34 of the frame 32 in position to be in line with the opening of the tube 41 of the next adjacent wall unit and these nuts receive one end of bolt 43, the heads 47 of each of these bolts being drawn down against the base of the channel 34 and being of a height that the base of the channel 34 of the next adjacent wall unit will be engaged by the opposite side of the head 47.

In addition to the bolts, wooden tongues 33 are fitted into the meeting channel sections and, if desired, these runners may be secured in place by screws as shown in Fig. 10. In both the wall and floor units these tongues serve to equalize and distribute any load stresses on the units. Likewise, as shown in Fig. 10, if a plurality of wall or floor sections are arranged end to end, the adjacent cross channels 34 are fitted with tongues 85.

In order to distribute the load and prevent lateral movement of the floor units where the joint of two adjacent floor units occurs between posts, a T plate 84 (Fig. 7) having a tongue portion 86 fitting in the channels 34 of the frames 32 of the floor units 28 is screwed or bolted in place to the frames 32.

While by these several arrangements it is seen that the wall sections and the floor and ceiling sections are securely locked together with no opportunity to sag and with all loads equally dis-

tributed, yet the sections may be readily assembled and disassembled.

Having described the several methods of interlocking the wall sections, one method of assembling the wall is to begin at a door opening shown in Fig. 5 with a post unit 17, connect the several wall and post sections together until another door opening is reached, and continuing around the wall until the same is completed by the first door opening.

The door openings are covered by door jamb 141 which is provided with vertical channels 142 mating with the channels 51 of the post unit as described in connection with Fig. 3, the post and wall units are locked together as described in connection with Fig. 8 and the door jamb is fitted in place over the exposed heads 79 of the doors and over the tongues which fit into the channels 51 and 141. With the door jamb in place, the same is secured to the H column 50 (or the adjacent frame of a wall unit) by screws 143, the heads of which are counter-sunk in the door jamb and the screw threaded ends of which engage the H column (or the metallic frame) as shown in Fig. 5. In this manner the wall and post units are securely locked together after which the door jambs are fitted in place to cover the exposed parts. By removal of the door jamb the wall and post units can be unlocked and readily dis-assembled.

The floor units are supported in the center of the building by posts 88 (Fig. 6) with top plate 90 resting upon the top of the H column 92 of the post. At the bottom each post 88 is supported by an arrangement comprising a pair of runners 98 and 100 extending longitudinally of the building, secured to the floor and spaced apart to form channel 102 with which registers a tongue 96 secured to plate 94 on the bottom of the post, the runners being covered with a metallic sheath 104.

After the flooring, side, end and center walls have been assembled and locked in place, and the desired number of floors of the building have been erected, the ceiling of the upper floor comprising sections 114 (Fig. 2) are located in place. These sections may be of the same general construction as the floor units, but the upper surface thereof need not be finished off unless desired. These sections also are interlocked as above described. The anchoring to the posts is by means of a tongue 60 which fits in a channel 40 of a portion 38 of the adjacent section 114, the tongue being secured to plate 116 which extends completely over the H column of post 118.

From Fig. 2 it will be noted that the sections 114 extend out beyond the side wall, and that the section 38 of denser material is not adjacent the end of the frame as in the case of the floor units heretofore described. The extended portion has a decorative molding or slab 120 secured thereto, the molding extending above the sections 114.

An angle iron plate 128 (Fig. 2) rests on top of the portion 38 of sections 114 and is secured to the column plate 116 by bolts 126. The plate 128 supports a triangular shaped runner 130 which is recessed to provide a tongue 132 and ledge 134, the tongue fitting in the channels 34 of frames 32 of roof units 136, which may be constructed and interlocked in the same general way as the side wall and floor units. The described mounting is for a peaked roof.

At the peak 131 (Fig. 2A) of roof units 136 is mounted ridge piece 133 having faces 135 ar-

ranged at right angles to the slant of the roof. Angle plate 137 having tongue 139 on one leg thereof is secured to the lower faces of ridge piece 133, the tongue 139 fitting into adjacent channels 34 of the frames of the roof units 136, and the other leg of the angle plate 137 supporting the underside of the roof unit.

Secured to an H shaped column 138 (which need not be molded in cement) are a pair of angles 143 which support and lock in place the upper ends of the roof units 136 by being secured to the exposed leg of angle plate 137, and also by bolt 147 passing through the units 136, the angles 137 and 143. The bottom end of column 138 may be similar in construction and mounting to center post 88 (Fig. 6).

In addition to the foregoing, tie rods 149 may be secured to plates 128 by the bolts 126 to prevent any lateral movement taking place in the roof assembly.

As shown in Fig. 2, the molding 120 with the upright side of the angle 128 forms a gutter 122. The gutter may be lined with metal as indicated at 140, which may be the metal normally used for the "flashing" about roof joints.

The unfinished spaces which occur where the floor sections are joined to the post and wall sections, may be finished off with decorative molding as indicated at 112, or the same material as is used to finish off the outer surfaces of the wall sections may be filled into the spaces by hand trowelling.

One method of mounting the window jambs or frames is indicated in Fig. 9, which shows two of the posts 17 alongside the window opening 146. These posts have the vertical grooves 51 as heretofore described. The window jamb 147 is constructed with a projecting flange 148 on each side thereof, which flanges are adapted to fit into the vertical grooves 51 when the jamb is slid in place with the frame against the sides of the window opening 146.

Any of the cement mixtures referred to above, except the one employing excelsior, may be poured and tamped into the vertical grooves 51 around the flanges 148 to cement the window jamb in place. A window frame indicated at 149 of any usual and ordinary construction may be mounted in the window jamb 147.

If the window opening occurs between adjacent wall sections 12, the channels 34 of the frames 32 take the place of the vertical grooves 51.

In Figs. 11, 12 and 13 is shown in detail the novel method of the arrangement and the locking of my detachable wall sections shown as partitioning 26 in Fig. 1 and which may be used as partitioning for rooms, halls, offices, and the like, in any existing building. In constructing my wall partitioning sections the frames of alternate sections 150 are provided with locking means and the alternate sections 152 with lock receiving means. As shown in Fig. 13, the locking section 150 has a surrounding metal frame the sides of which are tapered as shown at 154 and have complementary flanged portions 156 and 158 with the flanges spaced apart forming tubular channels 160 therebetween for receiving locking bars 161, which are free to turn therein, and which extend approximately within one-third of the top of the wall section. At predetermined places the channels of the frame 154 are cut out as indicated at 164 (Figs. 12 and 13) to allow for the protrusion of hooks 166 on locking bars 161.

The adjoining partition sections 152 are provided with a surrounding metallic frame, the sides of which are tapered as indicated at 157 and have an offset with the offset formed to mate with the offset formed in the section 150 by the provision of the channel 160. Opposite each of the hooks 166 the frame 157 is slotted at 159 to permit the entrance of the hooks 166. Behind each of the slotted portions is fitted a metallic lined pocket 163 of a sufficient size and shape to permit the free movement of the hook 166 therein as the bar 161 is turned to lock and unlock the sections. On the interior of the frame there is mounted a semi-circular ledge or bar 165 which is positioned to be engaged by the hook 166 when the partition sections are locked together, the hook being of such a shape that as the bar is turned to cause the hook to engage the ledge, there is a cam-like action to force the sections into tightly locked connection.

The locking bars 161 are turned to lock and unlock the sections by the following arrangement: Beneath each partition section is provided a transverse pocket 170, as in all wall sections, for the reception of wiring cables, pipes, etc. The bar 161 terminates in pocket 170. At the bottom lock bar 161 is undercut at 171 below which is a hexagonal end 172. A spring 174 is secured at the base of the partition and is provided with a cutout portion 176 of a shape to set over and correspond with the hexagonal end 172, to prevent the bar from turning. To turn the locking bar 161 the spring 174 is compressed so that the cutout portion registers with undercut 171 in which position the locking bar can be turned freely. When the bar is turned to the locked or unlocked position the spring is released and the cutout portion again fits over the end 172.

The partition sections 150 and 152 may be provided with cross bracing bars 185 that are welded in place.

The partition sections are supported upon studs 186 having parts 187 and 188 at right angles thereto and respectively provided with channels 189 and 190. The upper channel 189 engages with the channel 182. The channel 180 fits in the groove between two spaced-apart parallel runners 192 and 194 which are secured to the floor. The runners 186 and 188 may be metal encased if desired. The mounting of the partition sections upon the studs provides the chamber 170 referred to above.

At the ceiling a pair of parallel runners 196 and 198 are secured in place upon the ceiling with a space therebetween. Into this space there projects a series of bars 200, these bars being housed in the upper portions of the channels 160 for the locking bars 161. The bars are held in their upwardly projecting position between the runners 196 and 198 by means of a coiled spring 202 which engages the lower end of each bar 200 and the upper end of the corresponding bar 161. The side frame 154 is provided with an elongated slot 204 (Fig. 12) and the bar 200 has a hole 206 therein for the reception of a tool whereby the bar may be moved to compress the spring to remove the bar 200 from between the runners 196 and 198 whenever it is desired to assemble or disassemble the partition wall. A molding 208 may be mounted at the ceiling on the outside of the runners 196 and 198, if desired.

The space 170 is adapted to be closed by baseboards 210 which may be readily detached by simple outward pull, the arrangement for this

purpose being shown in detail in Figs. 14, 15 and 16. The baseboard 210 has mounted thereon upper and lower notched spring members 212 and 214 respectively adapted to have the notched portion thereof engage with the channel 182 in the frame member 180 and the groove between the lower runners 192 and 194. One method of mounting the spring members 212 and 214 of the baseboard is to secure the same to a plate 216 which fits into a tapered groove 218 in the rear face of the baseboard, as shown in Fig. 16.

In Figs. 17 to 21 inclusive I have shown a method of mounting a hanging ceiling which may be used both in the fabricated style of house referred to above or in any existing room where it is desired to install the same as for example in installing a sound-proof ceiling, or where it is desired to cover exposed pipes, wiring, and the like.

A central ceiling section 242 is provided with a surrounding metallic frame, the sides 244 of which are tapered and provided with projecting offsets 246 and 248, as shown in Figs. 17 and 18. Secured to the frame 244 on each side are a plurality of straps 250 which in turn are removably secured to depending brackets 252 that are secured to the ceiling in any suitable manner.

A second ceiling section is indicated at 254 which section also has a surrounding metallic frame. On one side the metallic frame is flat as indicated at 256 and at the other side the frame is tapered and provided with a projecting offset 258. The frames are filled with sound deadening material for example, such as the magnesia plastic cement composition referred to above in which excelsior is an ingredient as indicated at 260, and this material may be provided with a surface coating 262 also of sound deadening character, such as the formula above in which sawdust is substituted for the excelsior. Instead of the smooth surface coating 262 a perforated covering 263 may be used, as indicated in Fig. 18. These fillings are by way of example and as in connection with the wall and floor sections the surface coating extends over the edges of the surrounding metallic frames. There is mounted along each of the side walls, or beam, supporting angle brackets 264.

When the ceiling of Figs. 17 and 18 is to be mounted in place, the central section 242 is first secured in place after which a section 254 is mounted in place so that the side thereof having the flat frame portion fits against the wall and rests upon the angle bracket 264 and with its projecting offset 258 resting upon the projecting offset 246. The weight of the section and the tapered side frame insures the tight fitting and proper aligning of the two ceiling sections. Another ceiling section 254 is similarly mounted on the opposite side of the central section 242 with its projecting ledge 258 engaging the projecting offset 248 of the central section 242.

In the illustration just described it is assumed that the space between a wall and a cross beam, or between beams, or between walls, can be spanned by three ceiling sections, although it will be understood that by constructing the frames of sections 254 on each side with stepped or offset portions and alternating the sections 242 and 254, a ceiling may be composed of any number of sections.

In cases where the length of the room makes it impractical to have a suspended section of that length, it is desirable that the adjacent suspended sections be provided with means for locking them

together, in which event the arrangements shown in Figs. 19 to 21 inclusive may be used. As will be seen, the suspended sections 242 have flat metallic frame portions at each end as indicated at 266 and these ends are supported by angle brackets 264 as outlined above. Where there are to be two aligned suspended sections, the sections are provided on their adjacent surfaces with channeled frames 268 and 270, which are adapted to receive a tongue 272, which arrangement will be well understood from the constructions discussed above. Along the meeting edges of the frames 268 and 270 are provided a plurality of pockets 274 for the reception of clips 276 which are shaped to fit over the meeting surfaces of the frames of the respective sections, including the channeled portions.

In Fig. 20 is shown the meeting ends 278 of the side sections 280 which correspond to the side sections 254 of the construction described in Figs. 17 and 18 in the arrangement where it becomes necessary to provide a plurality of ceiling sections end-to-end.

In Fig. 22 there is shown a modified arrangement for clamping the various sections together, replacing the bolts. In this figure two adjoining wall sections 282 and 284 are shown with their respective channeled frames 286. Each section has imbedded in the plastic material one or more transverse tubes 288 which extend between the channeled portions of the frame. The frames have apertures 290 which register with the tubes but which are of smaller dimensions. A clamping bolt 292 screw threaded at one end has mounted thereon a block 294 to which is pivotally mounted a pair of fingers 296 that are normally spring pressed apart. A plate 298 is also adjustably mounted upon the screw threaded position of the bolt 292. A coiled spring 300 engages the plate at one end and a fixed collar 302 at the other end. When the wall sections are assembled in place, a clamp is inserted through the several registering holes 290 until the fingers pass through beyond the frame 296 of the adjoining section in which position the fingers 296 will spread apart beyond the opening 290. The bolt 292 is then turned until the sections are firmly clamped together under the tension of the spring 300.

In the foregoing various compositions of plastic materials have been suggested by way of example but it is to be understood that these compositions may be varied, or other materials may be substituted.

From the foregoing it will be seen that I have provided in detail a house which may be constructed to have more than one floor, yet the house is constructed of pre-fabricated parts which may be produced in quantity at a factory and shipped to the location of the house, the whole may be readily assembled and dis-assembled, partitions may be readily arranged therein and shifted to new locations therein at the will of the owner, the house is sound-proofed and temperature-proofed, and the whole comprises a strong, sturdy construction with all the parts thoroughly and securely locked together, and all the loads and stresses evenly and widely distributed.

Modifications may be made in the arrangement and location of parts within the spirit and scope of my invention, and such modifications are intended to be covered by the appended claims.

I claim:

1. A prefabricated building of more than one

floor in height each floor comprising outer walls having a plurality of pre-cast posts formed with vertically extending grooves and horizontal projecting tongues, a plurality of pre-cast vertically disposed wall sections each having a surrounding channeled frame, the posts and wall sections abutting each other with the vertical grooves and the channels of the adjacent frames registering, tongues fitting in the registered grooves and channels, flooring and ceiling supported upon said posts and comprising a plurality of pre-cast sections each provided across at the ends thereof with horizontally extending grooves, the sections overlapping the posts and vertical wall sections with the grooves of the floor sections receiving the projecting tongues of the posts and also registering with the abutting channels of the frames of the vertical wall sections, and tongues fitting between the registering grooves and wall channels to securely join together the walls and floor and ceiling sections with posts.

2. A complete building of more than one floor in height and composed substantially entirely of prefabricated parts, each floor comprising outer walls formed of a plurality of pre-cast vertical posts and pre-cast wall sections abutting each other, means for interlocking the posts and wall sections together and carried thereby, an intermediate vertical wall comprising a plurality of pre-cast posts and pre-cast vertical wall sections assembled together and means for interlocking the posts and wall sections together, flooring and a ceiling units each comprising a plurality of pre-cast sections, and means for interlocking the sections together, these units abutting the assembled posts and vertical wall sections, separate means for interlocking the flooring and ceiling sections to the assembled outer and intermediate walls, a roof composed of a plurality of pre-cast sections and means for interlocking the sections together into a unit, and means for mounting the roof unit upon the uppermost of said walls.

3. A wall comprising a plurality of pre-cast sections composed of hardenable plastic material, each section having a plurality of transverse tubes embedded in the plastic material, nuts mounted on the sides of each section adjacent to but offset from the tubes, the sections being assembled together with the tubes of one section in alignment with the nuts of the next adjacent section, and bolts passing through the tubes of one section and engaging the nuts of the next adjacent section whereby the sections are securely bolted together.

4. A readily assembled and disassembled wall for use in buildings, the wall comprising a plurality of preformed sections of the requisite height, each section having a frame provided with offset side portions and filled with a hardenable plastic material, the offsets of alternate sections being complementary, each alternate section having a turnable rod mounted upon the frame along each side thereof, each rod having a plurality of clamping hooks mounted therealong, openings in the frame through which said hooks project, alternate sections having a clamping bar fast on the interior of the frame along each side thereof, pockets in each side of said section through which said hooks move when the aforesaid alternate sections are assembled together, the hooks being movable to a position to engage the bars to securely clamp the sections together, the turnable rods projecting below the frame, means below the frame for holding the rods in adjusted position, means for mounting the frames

above the floor, other means for maintaining the upper end of said wall in place, and including an element projecting from the sections of the wall, and a baseboard for closing the opening below the frames.

5. A complete building composed entirely of prefabricated parts, and comprising outer walls formed of a plurality of pre-cast studs and corner posts and pre-cast wall sections, each stud and post having a central metallic member with a surrounding hardenable magnesia cement composition body and vertically extending grooves in said cement body, each wall section having a surrounding channeled metallic frame and a hardenable magnesia cement composition filling therein, the posts and wall sections abutting each other with the vertical grooves and the channels of the adjacent frames registering, tongues fitting between and extending into the registered grooves and channels to interlock the sections and posts, and means joining the central metallic members and the adjacent metallic frames for securing the posts and wall sections together from sidewise movement.

10 6. A complete building composed substantially entirely of prefabricated parts, comprising outer walls formed of a plurality of pre-cast studs, corner posts, vertical wall sections, and floor and ceiling units assembled together, each stud and post having a central metallic member and a hardenable magnesia cement composition body with the ends of the metallic member projecting at the top and bottom of the studs and posts and also a tongue extending from side to side across the top and bottom of each post and stud, means for fastening the pre-cast vertical wall sections to the sides of the studs and posts to form a vertical wall, each floor and ceiling unit comprising a plurality of sections each having a surrounding channelled metallic frame and a hardenable magnesia cement composition filling therein, the sections abutting each other with the channels in adjacent frames registering, and tongues fitting the registering channels to form a unitary floor and ceiling unit, means providing grooves in the floor and ceiling unit, the unit being positioned with the grooves fitting the tongues on the tops and bottoms of the studs and posts and adjacent the projecting ends of the metallic members of the posts and studs, and means for fastening the floor and ceiling units to said projecting portions.

15 7. A building constructed of prefabricated parts and comprising pre-cast corner posts, studs and wall sections, the wall sections abutting each other and the posts and studs, each stud and post having a central metallic member and a surrounding body of hardenable plastic composition, each wall section comprising a surrounding metallic frame having openings in opposite sides thereof and a hardenable plastic composition filling for said frame, one or more tubes embedded in said filling and registering with opposite holes in the frame, bolts extending through said tubes, and means carried by the frames and engaged by said bolts to join adjacent frames together, the bolts of the sections abutting the posts and studs being secured to the central members thereof to complete the wall.

20 8. A building of more than one floor in height composed almost entirely of prefabricated parts, each floor comprising outer walls formed of a plurality of pre-cast abutting studs, posts, floor and ceiling units, and wall sections assembled together; each stud and post comprising a metallic

member, a hardenable plastic composition body with portions of the metallic member projecting outside the body at the top and bottom, and portions of interlocks carried by said body; each wall section comprising a surrounding metallic frame, a hardenable plastic composition filling therefor, horizontally disposed tubes embedded in the plastic composition and accessible through opposite sides of the frame, and portions of interlocks also carried by said sections; means for completing the adjacent interlocks of the studs, posts and wall sections when abutting each other, bolts passing through said tubes and secured in the frames of adjacent wall sections, or the metallic members of adjacent studs and posts; each flooring and ceiling unit comprising a plurality of sections each having a surrounding metallic frame, a hardenable plastic composition filling therefor, horizontally disposed tubes embedded in the plastic composition and accessible through opposite sides of said frames, and a portion of an interlock carried by each frame, the sections being assembled with the frames abutting, means for completing the interlocks between the adjacent sections when assembled together, and bolts passing through said tubes and secured in the frame of the adjacent section to also secure the adjacent sections together; means for interlocking together the outer walls and floor and ceiling units; and a roof supported upon the uppermost wall, said roof comprising a plurality of sections each surrounded by a metallic frame a hardenable plastic composition filling therefor, the sections being assembled together with the frames abutting, and means for interlocking the sections when assembled together; and means for securing the roof in place upon said walls.

9. A readily assembled and disassembled wall for buildings composed of a plurality of sections, each having a surrounding frame filled with a hardenable plastic material, and means for detachably locking the sections together so that any section of the wall may be removed or replaced without disassembling the entire wall, alternate sections carrying movable clamping means and alternate sections carrying means engaged by said clamping means to lock the sections together when the sections are assembled in place, and a rod extending outside of said frame and connected to each movable clamping means, said rod being operable to lock and unlock the same.

10. A complete building of more than one floor in height composed substantially entirely of pre-fabricated parts, each floor comprising outer walls having a plurality of pre-cast posts each carrying a portion of an interlock at the sides thereof, a plurality of pre-cast wall sections each carrying a portion of an interlock of the sides thereof and abutting said posts, means for com-

pleting the interlocks to securely fasten the posts and wall sections together into unitary walls, flooring and ceiling comprising a plurality of pre-cast sections each carrying a portion of an interlock at each side thereof, means for completing the latter interlocks to securely fasten the sections together into a unitary floor and ceiling, means upon said posts for supporting the unitary floor and ceiling thereupon and securing the same to the posts, a plurality of pre-cast sections each carrying a portion of an interlock at each side thereof, means for completing the latter interlocks to securely fasten the sections together into a unitary roof, and means for supporting the unitary roof with said posts and securing the same thereto.

11. In a building construction, a continuous wall constructed of a plurality of abutting and aligned pre-cast posts and pre-cast wall sections respectively provided with registering vertical grooves on the abutting faces, a window jamb fitting between and having a shoulder portion abutting certain of the posts and wall sections and also having outwardly projecting flanges at the sides thereof engaging in the adjacent vertical grooves, means securing the flanges in place in the grooves, and means engaging the registering grooves to secure the posts, wall sections and window jamb together.

12. In a building construction, a continuous wall constructed of a plurality of abutting and aligned pre-cast posts and pre-cast wall sections, a door jamb fitting between and abutting certain of the aligned posts and wall sections, the jamb having inwardly projecting side portions extending into mating openings in the abutting posts and wall sections and also having a portion overlying the abutting face of the post and wall section, means carried by the frame to aid in positioning the jamb, means securing the jamb to the adjacent post and wall sections, and means for interlocking the abutting posts and wall sections to secure the posts, wall sections and door jamb together.

13. A readily assembled and dis-assembled wall for buildings composed of a plurality of wall sections each having a surrounding frame in which is a hardenable plastic material, engageable means carried at each side of alternate sections, movable clamping means carried at each side of alternate sections, said wall sections being mounted side by side and abutting each other with the sections being alternately arranged, the movable clamping means being operable to engage the engageable means to lock the sections together, the clamping means and engageable means being so constructed and arranged that any section of the wall may be removed or replaced without dis-assembling the entire wall.
